UNITED STATES PATENT OFFICE

RICHARD S. COWAN, OF FORT WORTH, TEXAS, ASSIGNOR TO GENERAL ICE SCORING MACHINE CO., OF FORT WORTH, TEXAS, A CORPORATION OF DELAWARE

ICE SCORING MACHINE

Application filed June 22, 1928. Serial No. 287,435.

This invention relates to machines for use in scoring ice cakes or blocks to form surface scores along which the cakes or blocks are to be split into smaller cakes or blocks which are usually of predetermined content and size.

An object of the invention is to provide a machine embodying novel scoring devices for forming transverse and longitudinal scores on cakes or blocks of ice so that such cakes or blocks may easily be broken up.

Another object of the invention is to provide a machine embodying said novel scoring devices, in combination with means for moving a cake or block of ice into engagement with the operating scoring devices.

Other objects will appear from the following description, reference being made to the drawings in which

Fig. 1 is a side elevation of an ice scoring machine embodying the present invention.

Fig. 2 is a front end elevation of the machine, a part of the frame being removed and a part shown in section.

Fig. 3 is a rear end elevation.

Fig. 4 is a cross sectional view of one of the scoring devices approximately on the line 4—4 of Fig. 5.

Fig. 5 is an enlarged side elevation of a portion of one of the scoring devices.

Fig. 6 is a view showing a pivoted support for one of the machine elements.

The machine in which the present embodiment is shown comprises a rigid vertical frame 1, a rigid vertical frame 2 and a rigid base 3 from which both frames 1 and 2 rise.

Each of the frames 1 and 2 supports a lower horizontal shaft 4 in bearings 5; and an upper horizontal shaft 6 in bearings 7. The shafts 6 are at equal heights above the shafts 4 and in the same vertical planes with the respective shafts 4 so that the shafts 4 are the same distance apart as the shafts 6.

To each of the shafts 6 a number of sprocket wheels 8 are attached, and a corresponding number of sprocket wheels 9 are attached to each of the shafts 4 so that a sprocket wheel 8 and a corresponding

sprocket wheel 9 constitutes a pair of sprocket wheels in a vertical plane.

A sprocket chain comprising alternating links 10 and 12 is mounted on each pair of sprocket wheels 8 and 9 and on each link 12 of the respective chains a scoring element is mounted. As shown, each scoring element comprises a tooth 11 projecting from the link 12 embracing the adjacent ends of the link 12 between its sides and mounted on the link pivots 13. The link pivots 13 are removable, being held in position by removable pins 14 so that any links 10 or 12 may be removed and others replaced, etc., by merely removing the pins 14 from the pivot pins 13 and then removing said pivot pins to permit detachment of the scoring tooth or the link, or both.

These scoring teeth are of novel configuration, each having an edge 15 which is in a horizontal plane throughout the extent of movement in which the tooth performs a scoring operation on the ice cake or block; and an inclined edge 16 which constitutes a curved point 17 extending beyond the plane 15 of the edge 15 (Fig. 5) and which is of greater width than the thickness of the main portion of the tooth 11 (Fig. 4).

It is now clear that there are two series of endless chains, each of which series is spaced from the other, and a series of scoring teeth supported by each chain. Each of said chains is made up of the links 10 and 12 and includes a series of scoring teeth 11.

Each shaft 6 has a beveled gear 18 attached thereto. The gears 18 mesh with beveled gears 19 on a shaft 20. The gears 19 are between the shafts 6 and mesh with those portions of the gears 18 which are closest to each other, so that the shafts 6 are rotated in opposite directions in order to move the inner portions of the scoring devices downwardly, as indicated by the arrows 21 (Fig. 2). The shaft 20 is power driven as by connections 22 driven by a motor 23 mounted on the machine frame.

Each of the scoring devices described may be held properly tensioned by a device provided for that purpose. As shown, for each scoring device an arm 24 is pivoted on the frame.

corresponding shaft 6 and supports an idler roller 25 against the inner side of the ascending portion of the corresponding chain 10. For each arm 24 an adjustable abutment 26 is provided. These abutments are in the form of screws operative in the upper portions of the frames 1 and 2, respectively, to engage and force inwardly the upper ends of the respective arms 24 and thus press the idler rollers 25 outwardly against the ascending portions of the chains 10 to take up any slack in and tension said chains.

A pair of rock shafts 27 are mounted in cross connections 28 at the top of the machine frame and each of said shafts supports a pair of depending arms 29. The lower ends of the arms 29 terminate in the same horizontal plane and are pivotally connected with the upper ends of the sides of frames 30 (Fig. 2). The frames 30 are wholly supported by the arms 29 so that, when said arms 29 are swung laterally in either direction, the frames 30 swing therewith, the lower portions 31 of said frames 30 being constantly in a horizontal plane. One of the arms 29 supports an element 32 rotative on a horizontal axis and having a threaded hole therethrough (Fig. 2). A screw 33 extends through the threaded hole in the element 32 and is rotative in either direction by a crank 34 mounted in a solid bearing 35 so that the inner end of the screw 33 may swing in a vertical plane with the element 32. Longitudinal movement of the screw 33 in an outward direction is prevented by a collar 36 and longitudinal movement of said screw in an inward direction is prevented by a collar 36^a. These collars permit the inner end of the screw 33 to swing vertically as required to move the element 32 and thereby its supporting arm 29. A platform 37 is supported by the frames 30 and is designed and adapted to support the cake or block of ice during the scoring operations.

A rod 38 is mounted for rocking movements in bearings 39 supported by the frame 2 and is provided on one end with a handle 40 and on the opposite end with an arm 41. This rod may be turned to place the arm 41 in position to serve as an abutment to stop a cake or block of ice on the swinging frame for operation of the vertical scorers described. After the vertical scorers have operated to form scores in opposite sides of the cake or block of ice the rod 38 may be turned to move the arm 41 out of the way so as to permit the cake or block of ice to be moved from the machine.

As the cake or block of ice moves from the machine it is scored horizontally by peripherally toothed annular scoring devices 42 attached to vertical rotary shafts 43 having beveled gears 44 on their upper ends meshing with the gears 18.

15 An actuator for moving the cake or block

of ice through the machine is shown, the same comprising a sprocket chain 45 mounted on a pair of sprocket wheels 46 on rotary shafts 47. The sprocket chain 45 supports a pair of arms 48 arranged to engage the end of the cake or block of ice in the machine and to move said cake or block from the machine after operation of the vertical scorers. During such movement of the cake or block of ice from the machine the horizontal scorers 42 operate to form horizontal scores on opposite sides of the cake or block.

Fig. 1 shows a cake or block of ice after it has been scored to form a number of defined sections 49 of predetermined weight, such as fifty pounds each, and a number of other sections 50 of predetermined weight, such as twenty-five pounds each. The cake or block of ice having these parallel score lines in opposite sides is easily broken into these smaller sections.

In operation of the machine a large cake or block of ice is placed in the frames 30 upon the platform 37. Then the crank 34 is operated first in one direction to swing the frames 30 a distance sufficient to carry the cake of ice against the vertically movable scorers at one side of the machine to form parallel vertical scorer lines; and then the crank 34 is rotated in the opposite direction to swing the frames 30 to position to carry the cake of ice to the vertical scorers at the other side of the machine to form vertical scores on the opposite side of the cake of ice parallel with and opposite from the first formed vertical scores. Then, the crank 34 is operated to move the frames 30 to their intermediate positions, after which the sprocket chain 45 is operated by a crank 57 on one of the shafts 47 to move the cake or block of ice from the machine, during which movement the scorers 42 form parallel horizontal scores on opposite sides of the cake or block of ice crossing the vertical scores. As stated, the large cake or block of ice may then be easily separated into these smaller sections.

The construction and arrangement of the parts of this machine may be varied within equivalent limits without departure from the nature and principle thereof. I contemplate such variations as may be found desirable, and what I claim and desire to secure by Letters Patent is:

1. A scoring machine comprising a number of vertically operative scorers, a swingable frame supported between said scorers, means for supporting a block of ice on said frame, and means for swinging said frame to move the block of ice into contact with the scorers first at one side and then with the scorers at the opposite side.

2. A scoring machine comprising a number of vertically operative scorers, a swingable frame supported between said scorers, means for supporting a block of ice on said

frame, means for swinging said frame to move the block of ice into contact with the scorers first at one side and then with the scorers at the opposite side, and an actuator supported above the block of ice and independently of said frame for moving the block of ice from said frame.

3. A scoring machine comprising a number of vertically operative scorers, a swingable frame supported between said scorers, means for supporting a block of ice on said frame, means for swinging said frame to move the block of ice into contact with the scorers first at one side and then with the scorers at the opposite side, a pair of shafts supported independently of said frame, an actuator mounted on said shafts for moving the block of ice from said frame, means for rotating one of said shafts to operate said actuator, and scoring devices for forming horizontal scores on opposite sides of the block of ice as the block moves from said frame.

4. An ice scoring machine comprising two series of endless chains, each of which series is spaced from the other, a series of scoring teeth supported by each chain, and means for supporting and moving a block of ice alternately into engagement with the scoring teeth on the respective series of chains.

5. An ice scoring machine comprising two series of endless chains, each of which series is spaced from the other, a series of scoring teeth supported by each chain, means for supporting and moving a block of ice alternately into engagement with the scoring teeth on the respective series of chains, and means supported independently of said supporting means for moving the block of ice from between said series of scoring teeth.

6. An ice scoring machine comprising two series of endless chains, each of which series is spaced from the other, a series of scoring teeth supported by each chain, a frame for supporting and moving a block of ice alternately into engagement with the two series of scoring teeth on the respective series of chains, a device for moving said frame laterally in opposite directions, means supported independently of said frame for moving the block of ice from between said series of scoring teeth, and means for forming scores on opposite sides of the block of ice transversely of the scores formed by said scoring teeth as an incident to movement of the block of ice as aforesaid.

7. A scoring machine comprising two series of spaced vertical scoring devices each of which series is spaced laterally from the other, and means for supporting and moving a block of ice laterally alternately into engagement with the two series of scoring devices.

8. An ice scoring machine comprising two series of spaced scoring elements each of

which series is spaced laterally from the other, a frame for supporting a block of ice, means for supporting said frame for lateral swinging movements to move the block of ice alternately into engagement with said series of scoring elements, and means for swinging said frame laterally.
